(57) **CLAIM**

The ornamental design for a shower head, as shown and described.

DESCRIPTION

FIG. 1 is a front elevational view of a shower head showing my new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a left-front-top perspective view thereof; and,

FIG. 8 is a reference view of the usage.

The broken line showing is included for the purpose of illustrating and forms no part of the claimed design.
